UNITED STATES PATENT OFFICE.

PENROSE E. CHAPMAN, OF ST. LOUIS, MISSOURI.

UNREELING AND TENSION DEVICE

1,396,728.

Specification of Letters Patent. Patented Nov. 15, 1921.

Application filed April 24, 1917. Serial No. 164,115.

To all whom it may concern:

Be it known that I, PENROSE E. CHAPMAN, a citizen of the United States, residing at St. Louis, State of Missouri, have invented 5 a certain new and useful Improvement in Unreeling and Tension Devices, of which the following is a full, clear, and exact description, such as will enable others skilled in the art to which it appertains to make 10 and use the same, reference being had to the accompanying drawings, forming part of this specification.

The object of my invention is particularly 15 to provide a payout reel holder and tension device which shall eliminate the troubles experienced when reels or spools of material such as "wire" string, etc., are paid out under heavy tension at high, intermittent, irregular, erratic or jerky speeds, with varying 20 weights and diameters of reel, inertia at starting, momentum at stopping, and which shall maintain a practically uniform tension on said wire in spite of the said and other variants, eliminate chattering of the 25 reel and do all this without injuring the finish, coating or covering of, or, the said wire itself and to provide easy and wide adjustability so that wires of very great differences in size may be handled by the same 30 machine.

For convenience throughout this document the word "wire" will be taken to include any and all elongated material such as wire both bare and insulated, thread, string, 35 rope, ribbon, cable or other materials which may be wound and unwound upon spools, reels, drums, bobbins, forms, coils or in self supporting rotatable "package", hanks, etc., and the word "reel" will be taken to include 40 any and all types of said rotatable "packages" of said elongated material.

While this invention is capable of being operated in connection with any device or operation requiring wire fed to it, it will be 45 described in connection with an armature winding machine as, especially when of high speed, such machines probably introduce more difficulties into the problem of feeding the wire to them than any other. For they demand that the magnet wire shall be fed to them at a uniform tension which must be close to the elastic limit in spite of the difficulties enumerated above, and must take care of the erratic or jerky demand due to 50 the corners of the armature.

In the drawings Figure 1 is a perspective

view of one of my armature winding machines fully equipped with motor, supports, and accessories as is more fully described in my Patent 1,121,798, and my pending application Serial Number 877,167, filed December 14, 1914, and with automatically operating and controlling means that are the subject of this document.

Fig. 2 is a perspective view as seen from 65 the rear of the tension device and reel holder with other portions of the machine removed to avoid confusion.

Fig. 3 is a view showing an alternative form wherein a motor is directly connected 70 to the reel holder spindle and electrically controlled.

In all views all characters denoting the same parts are uniform.

1 indicates the head or armature winding 75 machine proper driven by an electric motor 3. The specific character of this machine is not material to the present invention and is therefore not described herein. It carries the core 2 of an armature meant to be wound. 80 4 indicates the controller for the motor and 5 a pedal for operating the controller. The support for the parts that have been described consists of several members designated 6, 7 and 8, but as these may be varied 85 within wide limits they need not be described in detail. 9 indicates a reel or spool of wire and 9' the wire passing from the said spool past the tension devices to be described and to the armature core 2. The reel is carried by a suitable support 10 and turns upon a spindle 11, being held thereon by a suitable locking nut 11'. 12 is the brake band on the spindle 11 and 13 a brake shoe co-operating therewith.

95 14 is a spring through which shoe 13 is actuated by means of connecting rod 15.

Brake shoe 13 carries an arm 13', which in turn carries idler pulley 13'' that is adapted to tighten loose belt 16. It in turn 100 is driven by pulley 17 carried by the motor 3.

18 is the main or body casting of the tension device proper hereinafter called the "face plate" which is secured to the reel 105 holder frame 10.

19 (Fig. 1) is a spring actuated arm hereinafter called the "take up arm" tipped with a pulley 19' over which the wire 9' runs. This arm 19 is in turn actuated 110 through its shaft 20 by the spring 21 (Fig. 2) and is coupled to the connecting rod 15.

by means of the tail crank 22 thus actuating the brake shoe 13.

The mechanism comprised by the parts 10, 19, 20, 21, 22, and 23 constitute means for measuring and determining the pulling force applied thereto by the wire 9', transmitting that force to other parts of the mechanism, as will be more fully described.

The point at which the connecting rod 15 10 pulls against the spring 14 determines the tension of the brake and must be altered as the springs 21 and 34 are wound up. To accomplish this the spring barrel 23 (which is driven by the gear 24 and its worm 25 and crank 26) has a spiral cam 27 attached to it, said spiral cam as it rotates moving the spring end of connecting link 15 along spring 14 through lever 28 its shaft 28' lever 29 and a spring connecting link 29' 15 which flexibly connects the said rod 15 with lever 29.

It will also be noted that this mechanism permits all springs to be adjusted simultaneously at one point viz. crank 26.

25 Additional tension is provided for the wire 9' by running it around the pulleys 30, 31, 32, pulleys 30 and 31 being rotatably mounted on rigid studs. Pulley 32, however, is mounted on a crank or arm 33 hereinafter called the "tension arm" which in turn is mounted on a quill 33' through which shaft 20 operates. Said quill is driven by a spring 34 (Fig. 2) shown at the cut-away behind spring 21, which spring is also 30 driven by the spring barrel 23 and its ap- 35 purtenances.

The parts 32, 33, 33', 34 and 23 comprise a second means or mechanism controlled by the tension applied to the wire as it is being 40 delivered from the reel to the winding mechanism.

The spring 34 actuates the tension arm 33 carrying its combination brake pulley 32 and when under tension presses the said 45 brake pulley against the first member of the floating brake system, 35, 35', 35'', 36, 36'. Brake shoes 35', 35'' being connected to the hub of 35 through the springs 36 and 36', the said hub of 35 floats on the end of 50 the quill 33' i. e., is loose and free to oscillate. When the combination brake sheave pulley 32 is pressed against the shoe 35 it in turn reacts against the pulleys 30 and 31 55 through said brake system. 33'' is a buffer spring to limit the travel of tension arm 33.

In Fig. 3, 37 is an electric motor directly connected to the spindle 11, and 38 is an arm used to actuate controller 39 which controls the action of said motor 37.

60 The operation of this tension device and reel holder is as follows:

Spool of wire 9 is slipped on the spindle 11, and secured by the spindle nut 11' the wire if it is of moderate size, then being 65 threaded as shown in Fig. 1, first upwardly

and over the take up arm pulley 19', thence downwardly and around the tension device pulley 30 crossing itself, around the pulley 31, crossing itself, thence downwardly and around the pulley 32 crossing again and upwardly to the winding machine and core, 1 and 2.

If the wire is small the full tension may be applied to the spool. Under these circumstances the wire is threaded over pulley 19' thence under pulley 32, etc., the tension braking system (35, 35', 35'', etc.) being then out of commission. This is accomplished by setting the neutral point of the spring 34 ahead of that of the spring 21 80 in a manner to release the pulley 32 from its brake shoe 35 ahead of the system controlled by take up arm 19 and its appurtenances.

When the winding machine starts to take up wire, take up arm 19 (being held in its 85 upward position by the spring 21) will travel downwardly paying out wire, and giving time for the inertia of the spool 9 to be overcome and the spool set in motion. At the same time that this "take up arm" travels 90 downwardly it either adjusts or entirely releases the brake shoe 13, through the spring 14, connecting rod 15, and tail crank 22, which is connected to the arm 19 by the shaft 20. The reaction therefore is not only to 95 adjust the brake 13, but to "cushion" the demands for wire upon the spool 9 giving it time to start without breaking the wire or suffering from excessive tension.

In the vast majority of cases this action 100 is sufficient: However, should the inertia of the spool become very great in comparison with the dimensions of the wire it may become desirable to give the spool a start in addition to entirely releasing the brake, and 105 this may be accomplished in many ways. The preferred form is as follows:

Attached to motor or main shaft of the winding machine is pulley 17 over which a loose belt 16 travels, in turn playing over a 110 sheave 12' upon spindle 11 in such a manner that ordinarily it exerts almost no influence on the said sheave 12' therefore none on the reel 9. When the releasing of the brake is not sufficient to allow the pull of the wire 115 9' to overcome the inertia of the spool, take up arm 19 continuously travels downwardly actuating the brake shoe 13, which carries the arm 13' and its idler pulley 13''. This pulley is thus forced against the belt 16 in a manner to tighten it up and cause it to actuate the sheave 12 and through it the spindle 11 and reel 9. Upon the reel acquiring sufficient speed the take up arm will travel upwardly taking up any excess of wire being paid out 125 and while doing so releasing the belt 16 then adjusting the brake 13.

Another good method of imparting an initial start is to apply a motor 37 directly to the spindle 11 as shown in Fig. 3 substi- 130

tuting an arm 38 for the arm and pulley 13' and 13" said arm 38 actuating a suitable controller 39 said controller controlling the action of the motor 37 to obtain substantially the results portrayed above.

When the demand for wire ceases the reverse of the above actions of course occurs the take up arm 19 taking up the slack paid out by the spool due to momentum, at the same time setting the brakes 13 tighter and tighter against the brake pulley 12 thus bringing the reel to rest.

Brake spring 14 allows the take up arm 19 considerable travel after brake shoe 13 goes into action.

On moderate and coarse sizes of wire all the tension may not be applied to the spool owing to the delivering turn cutting down through the wire remaining on the spool. It therefore becomes necessary to apply additional tension to the wire over that which may safely be applied through the spool. This I accomplish by an improvement upon the conventional pulley tension device where in the wire travels around pulleys which have a braking power applied to them. In the conventional tension device as just described the tension does not change or adjust to allow for the inertia and momentum of the spool, varying diameter and all the rest of the afore-mentioned variants. In order to maintain a high tension it is necessary to adjust or entirely release the tension on these pulleys at the instant of starting to allow for the inertia of the spool, which may become sufficient for all tension needs (or more), and I accomplish this object as follows:

The wire being wound around pulleys 30, 31, and 32 as explained, when wire is demanded the brake pulley 32, will be carried upwardly with the wire to such a point that it and its accompanying pulleys 30 and 31, slip the brakes and vice versa thus automatically adjusting the brake tension. Should the inertia of the spool at the start in spite of the take up arm be sufficient to supply either a portion or all of the tension, the pulley 32 will still further recede or pull away from the floating brake system 35 to 36' inclusive, thus if necessary entirely releasing itself and its neighboring pulleys 30 and 31. At stopping, when the momentum of the reel 9 pays out an excessive amount of wire, thereby lowering the tension on the wire, the pulley 32 under the influence of its spring 34 will recede and press harder against the brake system automatically increasing the tension on all three of the tension pulleys.

Owing to the fact that the take up arm travels over a limited area, it is necessary that the various functions thereof should take place at approximately the same position in travel, irrespective of the size of the

wire the device is handling, and this means that the spring 14, interposed between the said take up arm 19 and the brake shoe 13, should be adjustable in strength, and not simply wound up tighter as at first would be supposed and is equivalent to putting in a stiff spring for coarse wire, and substituting therefor a light spring for light wire. I overcome this objection by making the spring 14 preferably of a cantaliver type and leaf construction, *i. e.*, supported at one end the other end remaining free, and applying the braking tension through the connecting rod 15 to it at different distances from its base. This brake spring should be actuated at or near the tip for fine wire, and at or near the base for coarse wire, and intermediate for intermediate sizes, spiral cam 27 attached to the gear 24 controlling said actuating point, and being proportioned to preserve the correct adjustment between brake spring 14 and the springs 21 and 34, as hereinbefore described.

There are many modifications of my device that can be made without departing from the spirit of this invention, the ones shown being preferred forms.

I claim:

1. In a device of the character herein described, the combination of means for rotatably supporting a reel carrying wire, a brake mechanism acting to retard the free rotation of the reel, means acted upon by the wire in its course from the reel arranged to move as the tension thereon varies, means connecting the said movable means with the brake mechanism, including a resilient portion, and means for adjusting the active strength of said resilient portion.

2. In a device of the character herein described, the combination of means for rotatably supporting a reel carrying wire, a brake mechanism for acting to retard the free rotation of the reel, a take-up arm acting on the wire, a spring acting on the take-up arm, means for varying the force of the spring that acts on the arm, means for connecting the take-up arm with the brake mechanism, including a resilient portion, and means for simultaneously adjusting the active strength of the said resilient portion and the force of the spring that acts on the take-up arm.

3. The combination stated in claim 1 when the "resilient portion" of the connection between the brake mechanism and "movable means" is a cantaliver spring.

4. The combination stated in claims 1 and 3 where the means for adjusting the active strength of the cantaliver spring comprises a connection with the spring adjustable toward and from its free end.

5. In a device of the character herein described, the combination of a rotatably supported reel, a brake acting to retard the free

- rotation of the reel, a spring-actuated take-up arm bearing on the wire in its course and arranged to move as the draft thereon varies, connections between the take-up arm and the brake arranged to release the brake as the take-up arm moves due to increased draft upon the wire and to apply the brake as the draft on the wire diminishes, such connections including a spring, and means for adjusting the active strength of the said spring.
6. The combination stated in claim 5 when the spring in the connection between the take-up arm and the brake is a cantaliver spring and the means for adjusting the active strength of said spring are movable longitudinally thereof so as to engage therewith nearer to or farther from the free end thereof.
7. In a device of the character herein described, the combination of a rotatably supported reel carrying wire, a brake acting to retard the free rotation of the reel, a take-up arm bearing on the wire in its course and arranged to move as the draft thereon varies, a spring acting on the take-up arm, connections between the take-up arm and the brake arranged to release the brake as the take-up arm moves due to increased draft upon the wire and to apply the brake as the draft on the wire diminishes, such connections including a spring, means for varying the tension of the spring that acts upon the take-up arm, a cam movable with the means for adjusting the spring of the take-up arm, and means operated by the cam to vary the active strength of the spring included in the connection between the take-up arm and the brake.
8. In a device of the character herein described, the combination of means for rotatably supporting a wire-carrying reel, a brake device to retard the free rotation of the reel, means for applying additional tension to the wire delivered from the reel, and means controlled by the tension upon the wire for automatically controlling the brake of the reel and the means for applying tension to the wire.
9. In a device of the character herein described, the combination of means for rotatably supporting a wire-carrying reel, means bearing upon the wire and moved thereby as the pull on the wire being drawn off the reel varies, a brake for the reel, means for applying additional tension to the wire being drawn from the reel, and connections with the said means bearing upon and moved by the wire for operating both the brake for the reel and the devices for applying additional tension to the wire.
10. In a device of the character herein described the combination of means for supporting a reel, with a tension device, comprising a tension arm carrying a pulley, a brake shoe adapted to act with said pulley,

means for causing the said tension arm to press said pulley against said brake shoe in opposition to the pull of the material from said reel when passing around said pulley.

11. In a device of the character herein described the combination of means for supporting a reel, with a tension device consisting of a plurality of pulleys, a movable tension arm carrying one of said pulleys, a floating system of brake shoes, means for causing the said tension arm to press its pulley against a member of said floating brake shoe system in opposition to the pull of the material from said reel when passing around said pulley, means for causing the said floating brake system to react against opposing pulleys around which the said material may also travel.

12. In a device of the character herein described the combination with means for supporting a reel, of a tension device for the wire from the reel consisting of a plurality of pulleys, a tension arm carrying one of said pulleys, a brake shoe system the members of which are resiliently coupled together, means for causing the said tension arm to press its pulley against a member of said brake shoe system in opposition to the pull of the material from said reel when passing around said tension arm pulley, and means for causing the said brake system to react against an opposing pulley around which the said wire may also travel.

13. In a device of the character herein described the combination of means for supporting a reel, a tension device for the material from the reel consisting of a plurality of pulleys, a tension arm carrying one of said pulleys, a brake shoe system the members of which are resiliently coupled together, a spring for causing the said tension arm to press its pulley against a member of said brake shoe system in opposition to the pull of the material from said reel when passing around said tension arm pulley, and means for adjusting said spring.

14. In a device of the character herein described, the combination of rotatable means for supporting a wire-carrying reel, a brake operating upon the said reel, means for operating the brake controlled by the pull upon the wire from the reel, tension means acting on the wire, comprising a tension arm carrying a pulley with which the wire engages, a brake shoe adapted to co-act with the said pulley, and means for causing the tension arm to press the said pulley against the brake shoe in opposition to the pull of the wire from the reel in passing around the pulley.

15. In a device of the character herein described, the combination of rotatable means for supporting a wire-carrying reel, a brake to control the rotation of the reel, a take-up arm bearing upon the wire and

- 5 moved thereby as the pull thereon varies, which take-up arm controls the brake for the reel, a tension device acting on the wire in its course from the reel comprising a plurality of pulleys one of which is carried by a tension arm, a resiliently connected brake shoe system interacting with the said tension pulleys, the said tension arm being arranged to actuate the said brake system, 10 springs respectively acting on the take-up arm and the tension arm, and means for simultaneously adjusting the said springs.
- 15 16. In a device of the character herein described, the combination of rotatable means for supporting a wire-carrying reel, a brake for controlling the rotation of the reel, a take-up arm bearing upon the wire and moved thereby as the pull on the wire varies, such take-up arm controlling the 20 brake for the reel, connections between the take-up arm and the brake through which it is controlled, comprising a resilient link, means for varying the active strength of the said link, a tension device acting on the wire 25 in its course from the reel, comprising a plurality of pulleys, a resiliently connected brake shoe system interacting with the pulleys of the tension device, a tension arm carrying one of the pulleys and controlling 30 the brake system therefor, as the tension arm moves due to the varying pull of the wire, springs for the take-up arm and the tension arm respectively, and means for simultaneously adjusting these springs.
- 35 17. In a device of the character herein described, the combination of means for rotatably supporting a wire-carrying reel, a brake operating to control the reel, a movable take-up arm controlled by the pull 40 upon the wire arranged to operate the reel brake, means for applying tension to the wire in its course from the reel, springs operating on the said take-up arm and ten-
- sion device respectively, and means for simultaneously adjusting the said springs, 45 said means being arranged to set the neutral point of the said springs successively.
18. In a device of the character herein described, the combination of rotatable means for a wire-supporting reel, a brake controlling the reel, a take-up arm bearing upon the wire and moved thereby as the pull thereon varies, a connection between the take-up arm and the reel brake for operating the latter as the arm is moved, comprising a 50 resilient link in the connection, a tension device acting on the wire in its course from the reel and comprising a tension arm movable as the pull upon the wire varies, springs 55 for the said take-up arm and the tension device respectively, and means for simultaneously adjusting the active strength of the said springs and also the active strength of the resilient link.
19. In a device of the character herein described, the combination of means for supporting a wire carrying reel, a brake controlling the reel, means engaged by the wire and movable accordingly as the tension upon the wire varies, connections between the said 60 means and the brake whereby the latter is operated from the former, other means engaged by the wire and movable as the pull on the wire varies, means for imparting an initial start to the reel, and connections between the second mentioned means engaged by the wire and moved as the pull thereon varies, for controlling the reel-starting means.
- 75 In testimony whereof I have hereunto affixed my signature in the presence of two witnesses, this 20th day of April, 1917.
- PENROSE E. CHAPMAN.
